[57] CLAIM

The ornamental design of a multipurpose decorative lamp, as shown and described.

DESCRIPTION

FIG. 1 is a front perspective view of the multipuse decorative lamp of our design;

FIG. 2 is a front view thereof when the light disc of the lamp is aligned in a horizontal orientation;

FIG. 3 is a right side view thereof, the left side view being a mirror image of the left side view;

FIG. 4 is a rear view thereof;

FIG. 5 is a top view thereof;

FIG. 6 is a bottom view thereof; and,

FIG. 7 is a front view of an alternate embodiment of the multipurpose decorative lamp wherein the base portion is not provided with a groove for housing a power cord, it being understood that the second embodiment is otherwise identical to the first embodiment.
